UNITED STATES PATENT OFFICE

2,173,505

NUMBERED MOTION PICTURE FILM

John H. Clewell, Arlington, N. J., and Frank H. McCormick, Wilmington, Del., assignors to Du Pont Film Manufacturing Corporation, Wilmington, Del., a corporation of Delaware

Application April 12, 1928, Serial No. 269,594

8 Claims. (Cl. 95—1.1)

This invention relates to photographic film used in the motion picture art, and particularly to such film carrying identifying indicia, especially footage numbers, thereon. In detail, film according to the present invention carries indicia which are visible upon the unexposed and undeveloped film, will not deteriorate during long-continued storage of the film, will not be removed upon subjection of the film to washing and developing fluids, and can be readily applied. It is a major object of the invention to provide a film having the indicated, and other, desirable characteristics. To these ends and also to improve generally upon films and their manufacture, the invention consists in the various matters hereinafter described and claimed.

Heretofore, numbers have been applied to film by photographing them thereon, the numbers appearing only upon the development of the film after its regular exposure in the camera. Among other disadvantages, such films have the following:—The numbers are not usable (because not visible) until after the film has been exposed in picture taking, and developed; the latent images of the numbers may fade during the storage between manufacture and use of the film; and the numbers will become indistinct and illegible should edge fogging of the film occur (the numbers being along the edge of the film between the extreme edge and the perforations). In film of the present invention these difficulties are eliminated and, in addition, the film has the desirable features above mentioned.

Without restricting the invention thereto, it is described with particular reference to the film illustrated in the accompanying drawing. In this drawing, the figure is a conventional broken out plan view of the film having numbers thereon in accordance with the invention, the numbers being substantially one foot apart, or at each sixty-fourth perforation, considering them as footage numbers.

In detailed accordance with the invention, the indicia are applied to the unexposed film F with chemical ink, i. e. are printed thereon, the ink being such that the indicia are firmly attached to the film, and are permanent against the washing and developing fluids, etc. Furthermore, the indicia are of such material that they will not injure the emulsion either by contact therewith or emanations from the indicia. If, as is desirable, the indicia are to be applied to the film by a continuous numbering machine, the ink is of such character that it will dry rapidly on the film but yet will print clearly without

blurring, and will not gum on the type. Furthermore, the ink should be of a type to be absorbed at least partially into the film, but should not shrink the perforations. An ink having these, and other, desirable characteristics may have the following composition for nitrocellulose or cellulose acetate film, no claim for the ink per se being made herein, the same being described and claimed in application Serial No. 269,595, filed April 12th, 1928 now Patent 1,806,965 by J. H. Clewell, one of the present inventors, and entitled Printing ink for cellulose ester bodies:—

	Grams
Diacetone alcohol.....	200
National nigrosine base N.....	20
Orange shellac.....	80

The above, it will be noted, comprises a solvent for either cellulose nitrate or acetate, e. g. diacetone alcohol, a dye, and a thickener, e. g. shellac. Any good nigrosine base may be substituted for the black one given. Blue ink can be made by the use of any of the spirit blues, and green by the use of malachite green or diamond green. Other suitable gums may be substituted for the shellac. The diacetone alcohol, boiling point about 160° C., represents a good cellulose ester solvent (and dye solvent) which gives sufficiently rapid drying without being too highly volatile. In making up the composition, dissolve the nigrosine in the alcohol, filter, and then add the shellac. The rate of drying can be increased by an addition of methyl acetone and decreased by an addition of triacetine.

It will be evident that the proportions of the ingredients may be considerably varied from those given above. An important feature is the use of a high-boiling solvent which has a strong solvent action on the material to be marked, and at the same time is a good solvent for dyes. The boiling point of the solvent should be high, so that the ink does not dry on the printing tool, but not so high as to retard its drying rate unduly. A boiling point between 140° C. and 225° C. is most suitable, but this range is not essential. When used on the plastic the ink sets quickly, largely by absorption into the plastic. Diacetone alcohol is a solvent which peculiarly meets these requirements. Other solvents which might be used are ethyl lactate, and diethylene glycol.

It will be apparent that a film comprised by the present invention can be produced by printing the indicia, e. g., consecutive numbers, dates, emulsion numbers, numbers relating to operation of machines, and so forth, on the base side of

the film. It is preferred to print the identifying data on the base side because such printing is less likely to cause damage to the sensitive coating, and it is particularly convenient to get the 5 necessary adhesion of the ink to the film.

Desirably, but not necessarily, the film may be printed by running the same through a printing machine of the type described in the patent to Conklin and Rocker, Patent 1,814,432, and entitled 10 Numbering machine. As is evident, the numbering of the film should be made by "safe" light, i. e., in a dark room, in order that the film shall not be exposed. The result is a film unexposed and undeveloped and carrying visible 15 indicia which remain upon the film through its various stages of use. As here shown, the indicia are properly printed (consecutively from end to end of the film) along the margin between the edge 2 and the perforations 3. In the drawing 20 the (prospective) picture areas are indicated at 4, as it is an unexposed film with which the invention is more particularly concerned.

We claim:

1. As a new article of manufacture a roll of 25 cinema film comprising in combination, a film base; having on one side thereof, nonsmeary, permanently indelible, ink-printed marginal indicia; the other side of said base supporting an unexposed light sensitive silver-halide emulsion 30 unfogged and unimpaired by its close association with said indicia in said roll; and cinematic marginal perforations in said film in spaced relation to said indicia, said perforations being undistorted by the application of said ink in the margin of said base.
2. As a new article of manufacture, a photographic film bearing on the rear side opaque impressions resistant to superficial liquid treatment and produced by means of an ink containing a 40 dyestuff and a cellulose ester solvent having a boiling point substantially between 140° C. and 225° C.
3. As a new article of manufacture, a photographic film bearing on the rear side opaque impressions resistant to superficial liquid treatment and produced by means of a solution of a dye- 45

stuff such as nigrosine base in a cellulose ester solvent having a boiling point substantially between 140° C. and 225° C.

4. An unexposed photographic film comprising a support composed principally of cellulose ester, a 5 light sensitive halide emulsion coated on one side of said support, the other side of said support having nonsmeary, non-fogging indelible ink printed indicia in the margin thereof.

5. Photographic raw film comprising a support 10 and on the front side of said support a photographic emulsion, the rear side of said support bearing photographically printable inscriptions consisting of a dye in combination with a colloid both having deeply penetrated the inner strata 15 of the support, said dye in combination with said colloid being fast to the action of the liquids which are used in the subsequent treatment of the film.

6. Photographic raw film comprising a support 20 and on the front side of said support a photographic emulsion, the rear side of said support carrying photographically printable inscriptions consisting of a dye in combination with shellac both having penetrated within the support, said 25 dye in combination with said shellac being fast to the action of the liquids which are used in the subsequent treatment of the film.

7. Photographic raw film comprising a support 30 and on the front side of said support a photographic emulsion, the rear side of said support carrying photographically printable inscriptions consisting of a coloring material in combination with a thickener both having penetrated within the support, said coloring material in combination with said thickener being fast to the action 35 of the liquids which are used in the subsequent treatment of the film.

8. A photographic film having ink-printed marginal indicia deposited within the body thereof 40 said indicia comprising a coloring matter and a thickener and being plainly visible throughout the useful life of said film.

JOHN H. CLEWELL.

FRANK H. McCORMICK.
